UNITED STATES PATENT OFFICE.

LYMAN GILMORE, JR., OF COLFAX, CALIFORNIA.

STEAM-MOTOR.

No. 825,385.

Specification of Letters Patent.

Patented July 10, 1906.

Application filed April 22, 1904. Serial No. 204,491.

To all whom it may concern:

Be it known that I, LYMAN GILMORE, Jr., a citizen of the United States, residing at Colfax, in the county of Placer and State of California, have invented certain new and useful improvements in Compound Steam-Motors; and I do hereby declare the following to be an exact description of my newly-invented compound steam-motor, which is especially simple in its construction and efficient in operation, which will economically utilize steam from a high to an extremely low pressure, which has but few working parts, affords direct connections from where the steam is liberated to the revolving shaft and belt-wheels, giving no chance for lost motion. The manner in which the steam is circulated around and upon each head independently, using it over and over, gives a very steady power and a high rate of speed.

My newly-constructed compound steam-motor is adapted to any purpose where a high-speed positive-acting economical motor is required, also readily adapted to any kind or class of work, and affords a powerful back gear.

The motor comprises but a minimum of operative parts and controlled entirely by one lever to start, stop, or reverse the same.

In order to obtain the best results from the steam, I have employed the ejector principle, which increases the volume of steam to be admitted to the cylinder with the same pressure per square inch as that of the live steam, thereby adding momentum to said increased volume, causing the same effect upon the driving capacity of the steam as that of the ejector, feeding the boiler against its own pressure by momentum alone. I have arranged the operative parts in such a manner as to convert every pound of steam into power, creating a driving force of the steam, a pressure and a compound action, bringing eight (8) of the piston-heads into continuous play with the steam and operate upon each head independently of the other, the operation and construction being so perfected as to render it impossible for the steam to pass out to the exhaust without first setting the motor revolving on its axis and performing the aforementioned steam operations, and I have particularly aimed at structural simplicity and economy.

In the motor which forms the subject-matter of this application I claim certain improvements over my copending application, Serial No. 100,306, in an improved form of the ejector principle, the same being a double

nozzle, in affording a direct course from the steam-chest through both nozzles to the cylinder, in an improved form of steam-passages, and in making the connections with the disk 6c and heads.

The especial objects of my improvements are, first, to provide a continuous discharging of steam from a set of small nozzles into a set of large nozzles, so as to create a suction 65 and discharge an increased volume of steam upon the heads of the cylinder; second, to afford facilities for the proper adjustment of the heads independently of each other in respect to the cylinder, semicircle depressions, 70 and central disk; third, the improved form of semicircle passages, so as to cut the circuit of steam off and on automatically and independently, influencing both the action of the impelling force of the steam and the suction upon the heads of the cylinder and to create a compound action of the steam upon each head independently of said suction and impelling force of the steam, and, fourth, to produce a positive double-acting and reversible motor controlled entirely by one lever and means for bringing eight (8) of the heads into continuous play with the impelling force, the suction, and the compound action of the steam through the medium of the ejectors and the semicircle depressions, &c., and to bring all of said steam operations to play upon a single revolving shaft through the medium of a central disk and to afford means for closing said steam-circuits and operations 90 by the manipulating of the lever J in the desired direction.

I attain the foregoing objects by the mechanism illustrated in the accompanying drawings, in which similar characters of reference 95 represent corresponding parts.

Figure 1 is a vertical longitudinal section of the motor. Fig. 2 is a vertical sectional view taken along the lines XX of Fig. 1. The central shaft C and belt and fly-wheels Y, 100 hereinafter referred to, are shown in elevation. Fig. 3 is a sectional view taken along the line 1 2 of Fig. 1, and Fig. 4 is one of the heads shown in perspective.

The piston-heads A are secured to the central disk B by screw-bolts *n n*, which pass through radial lugs *y y* on each side of the heads. The disk is secured on the central shaft C by a set-screw *a* and rotates within the cylinder D. The feed-pipe E, by which the motor is supplied with steam, is secured to and communicates with the steam-chest F

and from which lead the ejector-nozzles G and G², which lead into oppositely-placed receiving-nozzles H and H², which in turn lead, respectively, to opposite sides of the shaft C. In order to control the flow of steam through the nozzles G and G², I have provided the slide-valve I, which is operated by the lever J, connecting-rod d, and connecting-link f to start, stop, and reverse the motor, the lever J being fulcrumed and adapted to a toothed sector K, which is engaged by a pin e on the end of the rod g, the latter being connected with a handle h, pivoted on the lever J.

15 Above the nozzles G and G² are secondary valves L and L², respectively, which control the flow of the returning steam through conduits M and M² and the nozzles H and H² when the motor is reversed, thereby influencing the action of the suction directly upon the cylinder-heads. The valves L and L² are connected by the rod i, passing at the side of the nozzles G and G² and connected to the lever J by the connecting-link j on opposite side of the fulcrum thereof from the link f. Formed in the inner walls of the cylinder D are a series of recesses or semicircle depressions which extend nearly around the circumference of the cylinder, as shown by the letter N, beginning near the nozzle H and extending around the cylinder to near the nozzle H².

The exhaust is placed on the side of the cylinder opposite the nozzles H and H². The 35 back of the steam-chest P can be removed for admittance to the chest F by means of screw-nuts r r.

The motor is provided with a suitable base Q Q, and the sides of the cylinder are securely 40 clamped together by means of bolts R. Each of the piston-heads is provided with a peripheral ring W, which is secured to in place by means of set-screws v. Suitable packing-boxes T are provided, to which access is had 45 by means of screw-plugs U.

V represents antifriction-bearings, and X a key by which the fly-wheel is secured on the shaft C.

The motor is provided with the useful fly 50 and belt wheels Y and Z.

Having described the construction of my invention, I will explain its operation.

Assuming that the parts are in relative position shown, as the steam enters the chest F 55 and issues from the nozzle G it will discharge into the receiving-nozzle H, and a suction will be created at the rear of the nozzle H and through the nozzle H² and the conduit M², thereby creating a suction upon the heads 3, 4, 5, and 6, supplying the nozzle H 60 with hot steam from the exhaust, preventing condensation thereof and filling the nozzle H with an increased volume of steam which is discharged from said nozzle with its initial 65 pressure per square inch, impelling its in-

creased volume upon the heads opposite the nozzle H, the steam taking the course as represented by the arrows in Fig. 1. The steam from said nozzle is compressed against the head 7 and at the same time the steam previously compressed is expanding its power 70 against the heads 8 9 10 and exhausting at O, practically without pressure. At the exhaust a part of the steam is caught by the suction and acts upon the heads as aforesaid. The points of the depressions N are so constructed as to allow the steam to be cut off and on automatically and operate upon each head independently, as indicated by the dotted lines in Fig. 1. By operating the lever J the valve I will allow the steam to enter the nozzle H², while the valve L will open and the valve L² will close, thereby reversing the action of the motor.

I am aware that steam-motors have been 85 made with annular cylinders and also with heads rotating in such cylinders, also with ejector-nozzles discharging into said cylinders and I therefore do not claim such a combination broadly; but

What I claim is—

1. In a compound steam-motor, a cylinder having spaced semicircular recesses in its inner walls, a piston rotatably mounted in said cylinder and comprising a plurality of radial heads adapted to form steam-tight connections with the walls of the cylinder at points between said recesses, valve-controlled steam-conduits extending from points on opposite sides of the center of the piston, receiving-nozzles arranged parallel with said valve-controlled conduits and communicating therewith and with said cylinder, a steam-chest, tapering ejector-nozzles communicating with said steam-chest and receiving-nozzles respectively, and means for operating said valves.

2. In a steam-motor, a cylinder having spaced annularly-arranged recesses in its inner walls, and an exhaust, a piston rotatably mounted in said cylinder, and comprising a plurality of radial heads adapted to form steam-tight connections with the walls of the cylinder at points between said recesses, steam-conduits extending tangentially from points on opposite sides of the center of the piston, reciprocating valves controlling said conduits, receiving-nozzles communicating with said steam-conduits respectively and with said cylinder at opposite sides of the center of 110 said piston, a steam-chest, tapering ejector-nozzles of relatively small cross-diameter communicating with said steam-chest and extending into the outer ends of said receiving-nozzles, a valve controlling said ejector-nozzles, and means for operating the receiving-nozzle valves and the ejector-nozzle valves substantially in the manner and for the purpose set forth.

3. In a compound steam-motor, an annu- 115

lar cylinder having spaced annularly-arranged recesses in its inner walls, and an exhaust, a piston rotatably mounted in said cylinder and comprising a plurality of radial disk-like heads adapted to form steam-tight connections with the walls of the cylinder at points between said recesses, steam-conduits extending tangentially from points on opposite sides of the center of the piston, reciprocating valves controlling said conduits, tapering receiving-nozzles communicating at their larger ends with said steam-conduits respectively, and at their opposite ends with said cylinder at opposite sides of the center of said piston, a steam-chest, tapering ejector-noz-

zles of relatively small cross-diameter communicating with said steam-chest at their larger ends, and having their smaller ends extending into the outer ends of said receiving-nozzles, a reciprocating valve controlling 20 said ejector-nozzles, and means common to all of said valves, for operating same.

In testimony whereof I have signed my name to this specification in the presence of two subscribing witnesses.
